UNITED STATES PATENT OFFICE.

FRANK X. LAUTERBUR, OF SIDNEY, OHIO.

DESIGN FOR A DOUGH-MIXER.

58,035.

Specification for Design.

Patented May 31, 1921.

Application filed October 6, 1919. Serial No. 328,912. Term of patent 14 years.

To all whom it may concern:

Be it known that I, FRANK X. LAUTERBUR, a citizen of the United States of America, residing at Sidney, in the county of Shelby and State of Ohio, have invented a new, original, and ornamental Design for a Dough-Mixer, of which the following is a specification, reference being had to the accompanying drawing, forming part thereof.

The figure is a plan view of a dough mixer, showing my new design.

I claim:

The ornamental design for a dough mixer, as shown.

FRANK X. LAUTERBUR.
